UNITED STATES PATENT OFFICE

2,677,879

MANUFACTURE OF COAXIAL CONDUCTOR
ELECTRIC CABLES

John Colquhoun Beveridge, London, England, assignor to International Standard Electric Corporation, New York, N. Y., a corporation of Delaware

Application March 5, 1951, Serial No. 213,933

Claims priority, application Great Britain
March 10, 1950

3 Claims. (Cl. 29—203)

1

This invention relates to machines for applying insulating discs to conductors and in particular to conductors intended to form the inner conductors of coaxial communication cables.

Various methods of applying insulating discs preformed with central apertures on to conductors have been devised but the more commonly used ones involve pressing the disc onto the conductors laterally there being a radial cut in the disc to enable the conductor to pass into the central aperture.

U. S. Patent No. 2,092,487, filed April 24, 1936 and granted on September 7, 1937, there is described and claimed a machine for the continuous assembly of slotted discs in spaced relation on a wire in the manufacture of concentric conductor cables, in which the discs are supported in a rotating magazine which is moved to press the discs successively into engagement with the wire by reason of the relative movement between the magazine and the wire, the magazine being arranged to give to each disc during its application to the wire substantially the same velocity in the direction of travel of the wire as that of the wire itself, whereby relative longitudinal movement between the disc and the wire is eliminated during the pressing operation, means being provided for supporting the wire against bending during the application of the discs.

If the discs are made of a relatively rigid material, such as ebonite, slots having a width only slightly less than the diameter of the conductors are provided at the time of manufacture of the discs and it is desirable that successive discs should be applied to the conductor with the slots lying in different senses so as to avoid mechanical and electrical dissymmetry. In practice this means that at least two applicator wheels are required when slotted discs are used so that alternate discs can be applied from opposite sides.

If on the other hand the discs are made of a relatively resilient material such as for example, polythene, a simple radial cut or slit can be used in place of the slot of finite width and can be opened up sufficiently to permit the conductor to be passed into the central aperture after which the slit closes up again and the disc firmly embraces the inner conductor. When resilient discs are used the slits can be cut just before they are applied so that no problem of orienting them arises as it does when slotted discs are used. Furthermore, as the resilient discs close up after application it is not found necessary to arrange for the slits in alternate discs to lie in opposite senses. Hence it is possible to apply the discs

2

using one applicator wheel only. Such a machine is described in United Kingdom Patent 631,914 and granted on May 18, 1951. In this machine discs provided with central apertures, but not with slits, are fed from a supply hopper down a chute, the lower end of which is close to the upper part of a rotating applicator wheel mounted with its axis horizontal, and the discs are dropped one by one into the recesses in the periphery of the wheel. The discs are then carried round, past a slitting knife which makes the slits and a guide or key then engages the slits in the discs until they near the lower portion of the wheel when they are opened up by a wedge shaped member and applied to the conductor which is travelling tangentially to the wheel at the lowest point of its rotation and at a velocity equal to the tangential velocity of said wheel. Once the discs are in position on the conductor the slits close up and the discs are firmly held.

According to the present invention the applicator wheel is provided with an axially projecting peripheral flange having a plurality of slots extending through it and means are provided for feeding the apertured discs, the slots from the inside of the flange and for applying the slit discs to the conductor from the outside of the flange.

This arrangement enables the feed hopper for the discs to be arranged at a convenient height since the disc can now be fed to the applicator wheel at its lowest position instead of on the top as formerly whilst still maintaining a convenient height above floor level for the inner conductor since the discs can be applied to the conductor at the uppermost position of the applicator wheel.

The invention further provides a machine for manufacturing a coaxial conductor electric cable core having an outer conductor supported on disc shaped insulators centrally mounted in spaced relation on an inner conductor, comprising a wheel mounted with its axis horizontal and carrying near its periphery a slotted flange, each slot being so shaped as to receive one disc shaped insulator only, means for feeding centrally apertured insulating discs into successive slots at or near the lowest point of said wheel as it rotates, means for retaining the discs in the slots between the position at which they are fed into the slots and the position at which they are applied to the inner conductor, a knife in the path of the discs whilst they are being carried in said slots for slitting each disc from a point on its outer circumference to its central aperture, a guide member for keeping open the slits made by the knife, a wedge member for opening out

the slits to allow the discs to be applied to the inner conductor while it travels tangentially to said wheel at substantially the highest point of rotation thereof. The invention will be better understood from the following description of a preferred embodiment taken in conjunction with the accompanying drawings in which:

Figs. 1 and 2 are side and front elevations respectively of the machine.

Fig. 3 is an enlarged representation of part of the main applicator wheel shown in Fig. 2.

Fig. 4 is a section along the line IV—IV shown in Fig. 3.

Fig. 5 is a section along the line V—V shown in Fig. 3.

Fig. 6 is a section along the line VI—VI shown in Fig. 3.

Fig. 7 shows five sections along lines lettered *a*, *b*, *c*, *d*, *e* in the upper part of Fig. 3.

In Fig. 1 there is a supply hopper 1 which is kept supplied with discs 2 of insulating material, the discs being made with a central aperture of the correct size to fit on the inner conductor. The discs are transferred from the hopper 1 to the pick-up trough 3 by means of a travelling belt conveyor 4 which is preferably operated intermittently so as to keep the discs agitated. A hub 5 mounted in the trough 3 carries the four, identically shaped arms 6, 7, 8 and 9. The hub 5 with its arms is rotated and each of the arms is formed with a channel so that it picks up a number of the discs 2.

The arm 6 is shown when it has picked up four discs. In the position shown for arm 7 the end of the channel in the arm is directly above a slot in a fixed central boss 10 which can best be seen in Fig. 2.

From the slot in the boss 10 the discs enter a chute 11 and travel downwards under gravity until they are delivered to the inner side of the flange 12 of the main applicator wheel 13 which will be more fully described later. When the chute 11 is full any surplus discs delivered to the slot in the boss 10 are bypassed through a gate and fall back into the trough 3.

It can be seen that the applicator wheel 13 carries a flange 12 as shown in Fig. 1. The operation of the machine is primarily dependent on the functioning of this flange. The method of rotating the wheel is indicated and need not be more closely described. In Fig. 2 it can be seen that the flange 12 is in fact built up of a number of sections 14 separated by slots 15, and these sections 14 together form the applicator ring. In Fig. 3 there is shown in enlarged form part of the applicator wheel with details of associated equipment. Fig. 6 is a section through VI—VI shown in Fig. 3 and it can be seen that the section cuts the main wheel and the supporting arrangements 16 but does not cut any sections 14 as the section line passes through one of the gaps 15 between adjacent sections 14. In Fig. 6 it will be seen that there is a groove 17 in the section 14 and this, which occurs in every section 14, is also shown in Fig. 1. Effectively the flange or applicator ring 12 has a groove 17 on its outer surface all the way round. The purpose of the groove will become clear later.

Fig. 4 is a section through IV—IV shown in Fig. 3, and should be studied in conjunction therewith and also with Fig. 1. In this the discs 2 are seen approaching the lower end of the chute 11 while the section 14 is shown as cut by the section line the discs not being shown as cross hatched for clarity. As one of the slots

15 passes under the lower end of the chute 11 a disc falls in, the next disc in the chute being retained until another slot is in position.

Shortly after a disc has been dropped into one of the slots the continued rotation of the applicator ring brings it up against the slitting knife 18 which slits it from the circumference to the central aperture. An arcuate guide member 19 outside the applicator ring prevents the discs from falling through the slots and out of the applicator ring while a second arcuate guide member 20 on the inner side of the ring prevents the discs from falling out in the inward direction as they approach the upper position of the ring. The guide members 19 and 20 are mounted on the fixed part of the machine by means of supports 21.

Fig. 5 is a section through V—V shown in Fig. 3 and shows the knife 18 actually in the process of slitting a disc. Part of the external arcuate guide member 19 is formed as ridge or key 22, best seen in Fig. 7 (a).

This key 22 holds the slit in the disc 2 slightly open and prevents the disc from rotating, and in conjunction with guides 19 and 20 holds the disc in position in its slots 15 until the time has come when it is to be applied to the inner conductor 23. This ridge or key 22 is shown as a continuation of the knife 18.

This conductor is drawn tangentially across the applicator ring at its top point and at the same speed as the tangential speed of said top point and the conductor is pressed into the groove 17 by the support 24. It will have been noticed from Fig. 5 that the knife 18 projects into the groove 17 so that the slit in the disc is formed in the groove and will be held there by the key 22 all the time from the moment it leaves the knife 18 until it reaches the conductor 23.

Fig. 7 (a) shows as explained above how this key 22 holds the disc. Just before the disc reaches the inner conductor 23 however the key 22 is widened out to a wedge shape as shown in Figs. 7 (b), 7 (c) and 7 (d) so that the slit in the disc is opened further and further as the disc approaches the conductor until finally the key or wedge 22 tapers away to nothing and the slit in the disc closes over the conductor as shown in Fig. 7 (e).

The disc is now mounted on the conductors and passes away for the applicator ring to the next stage of the operation, normally the applying of an outer conductor. It is to be noted that the chute 11 leading from the pick-up trough 3 to the rotating flange 12 on the applicator wheel 13 is given two gentle bends in different planes, one to enable it to pass from the pick-up trough past the upper portion of the applicator wheel flange and into position to deliver the discs to the inner surface of the lower portion of the flange, the other to enable it to pass from the hub of the rotating pick up arms without interfering with the arms. These bends are such however, that the discs are able to fall under gravity down the chute and into the slots between the axially projecting portions of the applicator wheel and the chute is in fact substantially vertical.

While the principles of the invention have been described above in connection with specific embodiments and particular modifications thereof, it is to be clearly understood that this description is made only by way of example and not as a limitation on the scope of the invention.

What I claim is:

1. In a device of the character described, the

combination with a conductor drawn at uniform speed through a linear path, and means for gravity feed of centrally apertured circular discs to a point below said cable, of an annular and rotatably driven applicator for sequentially moving each disc from the point of feed upwardly and onto said moving conductor at a circumferential speed equal to the linear speed of the conductor, said applicator comprising a rotatably mounted and driven member provided with a plurality of laterally extending block-like elements disposed in circumferential configuration at spaced intervals to define a plurality of slots, equally spaced circumferentially, for the reception of a disc when in registry with said feed means, each said block-like element being centrally provided in the outermost wall thereof with a longitudinally extending slot, said slot being positioned in circumferential registry, guide means disposed between said feed point and the point of interception of said conductor for retention of each disc in its slot, means for feeding said discs to the inside of said block-like elements and into said slots, means adjacent said feed point and disposed in the path of said circumferentially registered slots for cutting each disc in the plane of applicator rotation and radially outwardly of the axis of applicator rotation, means for progressively spreading the slit portion of said disc as it is moved toward said conductor, and means adjacent the point of termination of said spreader means for directing said moving conductor into the path of said circumferentially registered slots and into the center of each disc, and said applicator applying said discs from the outside of said slots to said conductor, the slots serving as a passage-way through the block-like elements.

2. Apparatus for the sequential application of annular discs to a conductor comprising in combination, a rotatably mounted annular applicator peripherally provided with a laterally extending slotted flange, the slots providing a passageway through the flange, means for sequentially feeding a disc to the inside of the flange into each slot thereof, guide means for retaining the discs so

fed to the applicator against radial displacement inwardly and outwardly of the applicator from the point of feeding to the point of application to the conductor, cutting means disposed adjacent said disc feeding means and in the path of rotation of discs fed to the applicator for slitting each disc along the outermost radius as positioned by the applicator, annularly disposed spreader means for the progressive widening of said slits during rotation of the applicator, means tangentially disposed in respect to said applicator for feeding said conductor through the spread slit of each disc, and said applicator applying said discs from the outside of said slotted flange to said conductor.

3. The apparatus according to claim 2, wherein in said slotted flange comprises a plurality of arcuate block-like elements disposed in equally spaced annular configuration to define equally spaced disc receiving slots therebetween, said block-like elements each being provided in the outer wall thereof with an inwardly directed channel extending the length thereof, and said moving cable being tangentially directed into said block channels and centrally of each annular disc to permit, upon termination of said spreader means, snug fit application of each successive disc to said conductor.
